DESIGN FOR A DESK RECEPTACLE UNIT FOR
PENCILS, ENVELOPE OPENERS, RULERS,
OR THE LIKE

Gregory S. Dolgorukov, Detroit, Mich.

Application September 26, 1938, Serial No. 80,084

Term of patent 14 years

To all whom it may concern:

Be it known that I, Gregory S. Dolgorukov, a citizen of the United States, residing at Detroit, county of Wayne, State of Michigan, have invented a new, original, and ornamental Design for a Desk Receptacle Unit for Pencils, Envelope Openers, Rulers, or the like, of which the following is a specification, reference being had to the accompanying drawing, forming a part thereof.

The figure is a perspective view of a desk receptacle unit for pencils, envelope openers, rulers, or the like, showing my new design.

I claim:

The ornamental design for a desk receptacle unit for pencils, envelope openers, rulers or the like, as shown.

GREGORY S. DOLGORUKOV.
